UNITED STATES PATENT OFFICE.

PROKOP JACK PROKOP, OF NEW YORK, N. Y.

AIRSHIP.

1,244,367.

Specification of Letters Patent. Patented Oct. 23, 1917.

Application filed January 24, 1917. Serial No. 144,158.

To all whom it may concern:

Be it known that I, PROKOP J. PROKOP, a subject of the Emperor of Bohemia, and a resident of New York, in the county of 5 New York and State of New York, have invented certain new and useful Improvements in Airships, of which the following is a specification.

My invention relates to air navigating vessels of the heavier than air type, and among the objects thereof are to provide such vessels of relatively great speed through the application of a new principle, which may dispense with the usual supporting planes 10 if desired, which are very simple in construction and operation, and which may be made of very great load bearing capacity.

My invention is fully described in the following specification, of which the accompanying drawings form a part, in which like characters refer to like parts in each of the views, and in which:—

Figure 1 is a top plan view of an airship constructed in accordance with my invention;

Fig. 2 is a rear end view thereof;

Fig. 3 is an enlarged fragmentary section taken approximately on the line 3—3 of Fig. 1;

Fig. 4 is a similar section taken on the line 4—4 of Fig. 1;

Fig. 5 is a fragmentary section taken on a horizontal axial plane;

Fig. 6 is a view of a motor drive.

Referring to the drawings, 8 represents a projectile shaped body carrying horizontal tubular outriggers 9 at the ends of the cylindrical portion thereof and a landing frame provided with wheels 10, the conical head 11 having ventilating or observation windows 12 and carrying a propeller 13 on a shaft 15 driven by a motor 16, through the medium of a chain 17, interiorly of the body 8 as far below the axis of the body as 40 possible to stabilize the airship.

Inclosing the cylindrical part of the body is a sleeve 18 driven by means of an internal gear 19 therein and a chain of gears 20 projecting through the body into operative engagement with said internal gear, said sleeve being revoluble on the body 8 and being maintained in relative position by means of internal ribs 21, Fig. 5, having suitable bearings in the periphery of the body 8, preferably antifrictionally.

The sleeve 18 carries a plurality of spi-

rally arranged wings 22, shown as two in number although this is optional, of relatively great expanse centrally of their lengths and tapered toward the ends and 60 I prefer to provide triangular planes 23 at the front of the airship to fill the spaces within the respective outriggers 9 to which they are attached not taken up by the wings 22 in the revolution of the sleeve 18.

The outer ends of the respective outriggers 9 carry, each, a spring re-wound roller 24 for a flexible sheet 25 the outer edge of which is secured to a frame 26 the side rods of which are slidably arranged within the 70 respective tubular outriggers 9 and adapted to be forced outwardly by means of flexible shafts 27 within said outriggers operable by means of drums 28 driven by chains 29 in operative connection with the motor 16, 75 suitable guiding means being provided for the portions of the flexible shafts 27 not within the respective tubular outriggers.

The flexible sheets 25 constitute, when used, supporting planes and, when the flexible shafts 27 are drawn inwardly by their drums, will be wound on their respective rollers 24 to dispense with the use of said planes 25, as after the ship has reached a desired altitude above the earth after starting a trip.

Arranged at the rear of the body is a ball and socket joint 30 the ball of which carries a combined vertical and horizontal rudder and controllable by means of cables 31 90 or in any desired manner, the horizontal rudder 32 being used to vary the altitude and upon leaving the ground, and the vertical rudder 33 being for steering purposes.

The wings 22 will be revolved rapidly to 95 not alone drive the ship forwardly but also, when the ship is in the air, to support the ship aided by the triangular planes 23, and the forward movement is assisted by the propeller 13 of conventional type.

The body 8 and outrigger elements will always be maintained in horizontal position because of the gravity effect of the motor, passengers, stores, fuel, or other matter within said body, and the projectile shape thereof will offer little air resistance, while the wings 22 will serve not only as a drive but as a substitute for the conventional supporting planes.

My illustrations are for an operative structure though not developed as yet in practical details, and I reserve the right to alter

said details within the scope of the appended claim and within the spirit of the invention.

Having fully described my invention, what I claim as new, and desire to secure by 5 Letters Patent, is:

An airship, comprising a projectile shaped body, a motor therein below its center of gravity, a sleeve revoluble on said body and

geared to said motor, spirally arranged wings on said sleeve, guiding rudders, tubular outriggers carried by said body, a frame slidably movable in each pair of outriggers, a supporting plane carried by each frame, and means for rolling said planes upon the inward movement of said frames.

PROKOP JACK PROKOP.
